UNITED STATES PATENT OFFICE.

CHARLES A. DUNCAN AND GEORGE L. SHOUP, OF DULUTH, MINNESOTA, ASSIGNEES TO
AMERICAN CARBOLITE COMPANY, OF DULUTH, MINNESOTA, A CORPORATION OF
MINNESOTA.

ACETYLENE-GAS GENERATOR.

1,228,302.

Specification of Letters Patent.

Patented May 29, 1917.

Original application filed January 15, 1913, Serial No. 742,301. Divided and this application filed June 25, 1915. Serial No. 36,332.

To all whom it may concern:

Be it known that we, CHARLES A. DUNCAN and GEORGE L. SHOUP, citizens of the United States, residing at Duluth, in the 5 county of St. Louis and State of Minnesota, have invented certain new and useful Improvements in Acetylene-Gas Generators, of which the following is a specification, reference being had therein to the accompanying drawing.

Our invention relates to improvements in acetylene gas generators, the object of which is to provide a device of this character in which granular or dust carbid may be more 15 readily fed to the generator and be more quickly acted upon by water.

This case is a division of our application for "acetylene gas generators". Serial No. 742,301, filed January 15, 1913 patented 20 July 27, 1915, Number 1,148,364. This divisional application refers particularly to the means located within our generator for passing out the surplus water and residue from the carbid which has been fed into the 25 apparatus.

Other objects and advantages of the present improvement will be set forth in the following description and drawings in which—

The figure in the drawing is a vertical 30 sectional view through the center of our improved generator.

Referring now to the drawings in which like reference numerals designate similar parts, 1 represents the generator tank having at its upper end a removable cover held thereon by means of thumb-nuts 2', whereby access may be readily had to the interior of the generator. Extending across the upper end of the tank 1 and mounted within the 35 side walls thereof, a slight distance below the cover of the tank, is the carbid feed pipe 3. One end of said pipe extends beyond the tank and has connected thereto a coupling 5, to which is connected the carbid supply receptacle 6. The said coupling 5 is provided with a valve 5', whereby the carbid may be readily shut off from the supply pipe 3.

The carbid supply pipe 3, at the center of 50 the tank is provided with any suitable discharge opening not shown in its lower face and surrounded by the depending flange 4. Within the pipe 3 is suitably mounted the helical feed screw 7, which extends into the

coupling 5, and has its inner end terminating at a point directly above the center of the rectangular opening within the pipe 3. Said helical screw is provided with a shaft 8, which extends out through the opposite wall of the tank 1, and having means thereon for rotating the same, which will hereinafter be more fully described.

The upper end of the tank is provided with a water-supply pipe 9, and adapted to furnish a continuous supply of water to the 65 four depending nozzles 10, which surround the carbid as discharged from the opening 4' in the pipe 3. These nozzles furnish four spray-jets of water under pressure which catch the carbid dust as soon as it is discharged and immediately carry the same under the surface of the main body of water in the tank, thus making it impossible for the dust to collect in lumps on the upper surface of the water and to cause trouble, 70 such as has been heretofore found in generators where dust carbid has been used.

Connected to the water supply pipe 9, above the four jets 10, is a pipe 11, divided preferably into two sections and having in 80 their upper faces the perforations 12, by means of which the water is discharged upwardly against the under side of the cover 2, for the purpose of keeping the latter cool and also adding water to the generator and 85 to fill the entire upper portion of the tank with the precipitating spray which further insures the complete and instantaneous submersion of all dust and also washes the gas of impurities to a certain degree. Connected to the side of the tank 1 about midway of its height is a water overflow pipe 13, which has its lower end extending down within the tank to within a short distance of the bottom thereof. The pipe on the outside of the tank extends upwardly a relatively short distance and is then led off to any suitable place of discharge. At said discharge connection we preferably provide a short open-ended vertical section 14, to admit of the free expansion of the water in the event of the sudden depression of the water within the tank.

The lower end of the tank is provided with a horizontal shaft 15 which carries a 105 plurality of agitators 16, for the purpose of agitating the water in the bottom of the tank and thus preventing the collection

of hardened residue thereon. Attention is called to the fact that the blades of the two agitators, which are in the form of propeller wheels, have the blades of one wheel set 5 opposite to the body of the other whereby the sludge and water are thrown from the ends of the tank toward the center thereof. The arrangement of the blades of each propeller wheel is clearly shown in Fig. 1. Due 10 to the arrangement of the blades each propeller wheel thoroughly mixes one-half of the sludge with the water in the tank. One end of the shaft extends out through the tank 1 and is provided with a pulley 17, 15 by means of which the shaft is rotated. The shaft 15 is provided with a sprocket wheel 22 over which passes a chain 22', said chain passing upwardly over a sprocket wheel 23, carried by the shaft 8, whereby the shaft 20 8 is rotated for feeding the carbid to the machine. Mounted within the tank just above the shaft 15 is a float 18 carried by the bell-crank 19 which has a downwardly extending lug 21. The shaft 15 carries a series of lugs 20, rigidly fixed thereon and 25 when the water within the tank falls below a certain level the lug 21 engages the lugs 20 of the shaft 15 and locks the shaft against rotation. This locking of the shaft thereby 30 stops the feeding of the carbid.

Connected to the upper end of the tank 1, is the gas discharge pipe 28, leading to a gas storage tank, or wherever desired. Within the vertical portion 28' of the pipe 35 28, we install a small vertically disposed water supply pipe 30 having a discharge nozzle 30' in the uppermost end thereof, which discharges upwardly against the concave cap 35 supported by the pipe 30, causing a fine continuous spray of water discharging downwardly within the gas pipe 28' and thus washes and purifies the gas.

We also provide a second gas pipe 31 leading 40 from the generator tank from approximately the same level of the pipe 28, this being a safety discharge and leading well down into the water of the tank as at 32, so that in the event of an abnormal gas pressure arising within the tank the gas 45 would force out the water, uncover the lower end of this safety discharge pipe 32 and escape through it to the outside atmosphere. The safety discharge pipe 31 on the outside 50 of the tank is also connected to the discharge pipe 28 by cross-pipe 33, having a suitable shut-off valve 34 therein, so that any portion 55 of the gas generated may be exhausted to the outside atmosphere through this pipe 31 when desired.

60 The operation of our device is as follows: The device is set in motion by rotating the pulley 17 by a band, or in any other desired manner, which through the medium of the chain 22' and the sprocket 23, the shaft 8 65 is set in motion causing the worm 7 to feed

the carbid from the receptacle 6, through the pipe 3 and discharge it through the opening 4' into the tank, it being understood, of course, that the water supplies had previously been turned on and the tank supplied with the proper amount of water. As 70 the carbid is discharged through the opening 4' into the tank chamber it is immediately caught by the water jet spray from the nozzle 11 and carried directly under the 75 surface of the main body of water in the tank. Water is also supplied through the pipe 11, against the under side of the cover 2, whereby the entire upper end of the tank 80 is filled with a fine spray of water causing any of the dust that is in the tank above the water to be instantly precipitated, thus purifying the gas. When the water within the tank 1 falls below the float 18, the shaft 15 is locked, as heretofore described, which 85 stops the shafts 15 and 8 and causes the feed of the calcium carbid to cease. By this method of continuously mixing the carbid and water as they enter the tank and during precipitation therein it is evident that a 90 continuous discharge of water from the tank is essential and which is provided for by means of the discharge pipe 13 as above described.

This continuous discharge also provides 95 means whereby the residue carried by the water is being constantly removed from the tank which avoids any necessity of the tank being periodically cleaned and permits of continuous operation of the device.

As heretofore stated, this particular application refers to the specific feature of keeping the residuum constantly stirred up so that it is carried off by the discharging water, is exceedingly important in the successful working of the machine, in that it avoids the necessity of cleaning out, and permits continuous and uninterrupted operation.

Having thus fully described our invention 110 what we claim and desire to secure by Letters Patent is:

1. An acetylene gas generator, comprising a tank, a carbid feed in the upper end thereof, means for mixing water with the carbid fed into the tank, a transverse shaft located adjacent the bottom of the tank, two propeller wheels carried by the said shaft, the blades of one wheel set opposite the blades of the other, means for operating the said shaft whereby each propeller wheel thoroughly mixes one-half of the sludge with the water in the tank, a discharge pipe having one end adjacent the bottom of the tank and at a point below the propeller wheels, and its other end extending without the tank at the desired water level.

2. An acetylene gas generator comprising a tank, a rotary carbid feed in the upper end thereof, means for mixing water with

the carbid fed into the tank, a transverse shaft located adjacent the bottom of the tank, propeller wheels carried by the said shaft, a water and sludge discharge pipe, 5 unitary driving means for the carbid feed and the transverse shaft, and a float operated by the water in the tank having means carried thereby for locking the transverse shaft against rotation and thereby stopping 10 the carbid feed and the propeller wheels

when the water in the tank falls below the level of the float.

In testimony whereof we hereunto affix our signatures in the presence of two witnesses.

CHARLES A. DUNCAN.
GEORGE L. SHOUP.
